FISH HOOK DISGORGER

Percy W. Archer, 5 Thirsk Road, Northallerton, England

Filed Dec. 8, 1960, Ser. No. 63,188

Term of patent 7 years

(Cl. D31—4)

FIG. 4.

FIG. 5.

FIG. 6.

FIG. 2.

FIG. 3.

FIG. 7.

FIG. 1.

FIG. 1 is a perspective view of a fish hook disgorger showing my new design;

FIG. 2 is a front elevational view thereof;

FIG. 3 is a side elevational view thereof taken from the left of FIG. 2;

FIG. 4 is a bottom plan view thereof;

FIG. 5 is a top plan view thereof;

FIG. 6 is an enlarged, fragmentary perspective view of the probe end thereof; and

FIG. 7 is an enlarged, fragmentary perspective view of the grip end thereof.

I claim:

The ornamental design for a fish hook disgorger, as shown.
